CLAIM

The ornamental design for a ride height adjustment device as shown and described.

DESCRIPTION

FIG. 1 is a front view of a first ride height adjustment device showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is an exploded view thereof;

FIG. 9 is a front view of a second ride height adjustment device showing my new design;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view thereof; and,

FIG. 16 is an exploded view thereof.

Applicant expressly reserves the right to modify FIGS. 1-16 to show in broken-lines any and all features that are shown herein in solid lines and/or vice versa.

The present article is a ride height adjustment device for vehicles. As shown in the exploded view of the ride height adjustment device, a hydraulic cylinder shaft is inserted into a height adjuster, and a coil spring is supported by a spring catch of the height adjuster.
